(57) **CLAIM**

The ornamental design for a storage box with partitions, as shown and described.

DESCRIPTION

FIG. 1 is an exploded perspective front view of a storage box with partitions, showing my new design;

FIG. 2 is an enlarged front side view thereof;

FIG. 3 is an enlarged back side view thereof;

FIG. 4 is a left side view thereof;

FIG. 5 is a right side view thereof;

FIG. 6 is a top side view thereof, the partitions shown adjacent to the box for convenience of illustration; and,

FIG. 7 is a bottom side view thereof, the partitions shown adjacent to the box for convenience of illustration.
